ALFRED J. RUDOLPH, OF BYWOOD, PENNSYLVANIA

PRESSURE EQUALIZING MEANS FOR HEATING SYSTEMS

Application filed November 29, 1927. Serial No. 236,408.

In heating or similar systems in which the heating medium consists of a fluid such as water, steam or vapor, it is essential to the attainment of the best results that the pressures in the feed and return pipes be maintained in equalized relation to each other.

The object of the invention is to provide means of simple construction for embodiment in the feed and return lines of the system in proper relation to the heat-radiating elements or structures of the system to maintain an operative "balanced" relation between the pressures in the said feed and return lines.

15 It also is an object of the invention to provide means within the feed and return lines in opposed relation to each other and in operative relation to the heat-radiating elements or structures of the system for maintaining an operative "balanced" relation between the pressures and which at the same time will permit practically free passage or flow of the fluid through the said feed and return lines.

25 I shall not at this time undertake to indicate in greater detail the nature, scope and objects of the invention, but the character and the objects of the invention will be referred to or made apparent in and by the 30 detailed description thereof which follows:

In the drawings:

Fig. 1 is a view partly in elevation and partly in vertical section of feed and return pipe lines provided with means embodying the invention and showing in elevation an intermediate heat-radiating element or structure of the system and its connections to the said lines, the floor upon which the heat-radiating element is located being indicated in section.

Fig. 2 is a similar view showing a different arrangement of the feed and return pipe lines, in each of which, however, means embodying the invention is provided, as 45 illustrated.

In Fig. 1 of the drawings I have shown a heating element or radiator 1, to which a heating fluid is supplied through a horizontal section of pipe 2, the outer end of 50 which is connected to an opening in a nipple

or projection 3, provided upon one side of a device 4 which may be described as being of general Y-shape. To the opposite ends of the device 4 the adjoining opposed ends of sections 5 and 6, constituting parts of a supply pipe line, are connected. The opposite side of the heating element 1 is connected by means of a horizontal section of pipe 10 in like manner to the device 4 to the opposite ends of which the adjoining opposed ends of sections 5' and 6' of a return pipe line are connected. It will be understood that the supply line, including sections 5 and 6 and other similar sections, extends from the heated fluid supply, usually located in the bottom of a building, to the top of the building or to the topmost floor thereof which is supplied with heating means; and likewise that the return pipe line extends from the top of the building or from the topmost floor back to the source of heated fluid supply. This arrangement is as usual and will be understood by those skilled in the art.

As previously stated, the device 4 may be described as of general Y-shape. It is provided upon its interior with a tapered or V-shaped projection 11, which extends from what may be described as the outer side thereof inwardly toward the adjoining end of the pipe 2 or 10, as the case may be. The inner edge or end of the tapered or V-shaped portion 11 is so located that the areas between the same and the points *a* and *b* are substantially equal respectively to the internal transverse area of the respective pipes 5 and 5'; and also so that the area between the same and the point *c* is substantially equal to the internal transverse areas of the respective pipes 6 and 6'. Upon reference to the supply pipe line shown in Fig. 1 it will be apparent that as the heating fluid, such as water, steam or vapor, flows upwardly and as it passes from one section of the pipe to another it contacts with or impinges upon the inwardly and transversely extending tapered projection 11 and is deflected thereby toward the pipe 2 and to the heating element 1. This action results in a flow of or in a pressure tending to cause the fluid to flow toward and into the heating

element 1, but the flow of the fluid from the section 5 to the section 6 and through similar sections at other points in the system is not retarded to such an extent as to interfere 5 with the proper or necessary flow of the heating fluid upwardly through the said line. Likewise the pressure and flow of the fluid in the return pipe line are controlled. The contact with or impinging of 10 the fluid upon the upper side of the tapered or V-shaped projection 11 in the return pipe line causes a back pressure within the discharge line 10 from the heating element 1 to retard or which tends to retard the flow 15 of fluid from the said element. In other words, the devices 4, located in opposed relation to each other, the one in the supply pipe line and the other in the return pipe line, on opposite sides of the heating element 20 1, operate to maintain a proper relation of pressures and consequent flow of the heating fluid in the two lines and to thereby effect greater efficiency in operation of the system.

25 In Fig. 2 of the drawings I have shown a slightly modified construction in which two heating elements 1 are provided upon the same level or upon the same floor to which the heating fluid is supplied by a centrally disposed supply pipe line comprising sections 5 and 6, such as are shown in Fig. 1. Return pipe lines, comprising sections 5' and 6', are provided upon the opposite sides of the heat radiating elements or structures 30 1, as is shown. The devices 4 provided between the sections 5' and 6' in Fig. 2 are identical with the devices shown and correspondingly numbered in Fig. 1 of the drawings.

40 The adjoining opposed ends of the sections of pipe 5 and 6, constituting parts of the supply pipe line in Fig. 2, are united by means of a connecting device 4' similar in construction to the corresponding device previously designated by the numeral 4. The difference, however, is that the adjoining opposed ends of the horizontal sections of pipe 45 15 and 16 are united to the opposite ends of the said device, while the adjoining opposed ends of the sections 5 and 6 are connected to the opposite sides of the intermediate portion of said device. In other words, the upper end of the pipe 5 is secured in an opening provided in a projection 17 50 which corresponds to and extends in the direction of the tail of a Y, while the lower end or adjoining opposing end of the section 6 is secured in an opening provided in the opposite side of the device 4' in 55 opposed relation to the upper end of the section of pipe 5. The device 4' is provided with an inwardly extending projection 18 provided with an opening extending therethrough in which the lower end of the section 65 of pipe 6 is secured. The said projec-

tion terminates in opposed relation to the upper end of the pipe 5. Preferably the areas of the branch pipes of the device 4' in planes including the points *d* and *e* are equal to the internal transverse area of the pipe 5. The heating fluid, as it flows upwardly from the pipe 5 and as it is discharged into the chamber within the device 4', is divided into three streams or portions. Two of the streams flow in accordance with the principle of operation of the system to the right and to the left, respectively, and supply fluid to the heating elements 1 located upon opposite sides of the intermediate supply pipe line, while the third stream flows upwardly into and through the section of pipe 6.

It will be understood that there are as many sections of the pipes 5 and 6 and 5' and 6' in the system as there are different levels or floors to be heated.

The operation of the system as disclosed in Fig. 2 and the relation of the pressures between the two return pipe lines and the single supply pipe line are effected in accordance with the same principle and identically in the same way as has been set forth in the description of the simpler structure illustrated in Fig. 1 of the drawings.

It will be understood that the number of the supply and return pipe lines and heating elements or radiators may be selected to meet the conditions as they may exist in any particular building or structure which is to be heated, and also as may be required to meet the design of the architect or person designing and building the structure.

It will be seen that by my invention I have provided in a heating system novel means of simple construction operating in a manner to effect a proper relation between the pressures and the flow of the heating fluid in the supply and return pipe lines whereby the efficiency of the system may be greatly improved or enhanced.

Having thus described my invention, what I claim and desire to secure by Letters Patent is:—

1. A heating system comprising heat radiating means, a supply pipe for supplying a heated fluid to said means, a return pipe for conveying the said fluid from said heat radiating means, means for connecting the supply pipe to the said heat radiating means, means for connecting the said return pipe to the said heat radiating means, and means embodied in each of said pipes which tend to cause the heated fluid to flow therefrom through the said connections toward the said heat radiating means to thereby balance the pressures of the heated fluid in said heat radiating means.

2. A heating system comprising a heat radiating means, a supply pipe for supplying a heated fluid to the said heat radiating

means, a return pipe through which the heated fluid flows from said heat radiating means, a pipe connection between the said supply pipe and the said heat radiating means through which heated fluid is supplied from said supply pipe to the said heat radiating means, a pipe connection from the said heat radiating means to the said return pipe through which heated fluid flows from the said heat radiating means to the said return pipe, and means embodied in each said supply pipe and return pipe tending to cause the said fluid to flow in opposite directions through the said heat radiating means, the 15 said means embodied in each of said pipes permitting the fluid to flow freely through both the supply pipe and the return pipe.

3. Pressure equalizing means for heating systems which includes a supply pipe 20 through which a heated fluid flows, a return pipe through which said fluid flows, a connection including a heat radiator extending from the supply pipe to the return pipe through which said heated fluid flows, and 25 means in the supply and return pipes located in adjoining relation to the opposite ends of said connection, the said means tending to cause the fluid to flow in opposite directions through the said connection to thereby create opposing pressures in the said connection.

4. A heating system comprising a heat radiating element, a supply pipe for heated fluid, a return pipe through which fluid flows 35 from the said heat radiating elements, a horizontal pipe connection between the said heat radiating element and the said supply pipe, a horizontal pipe connection between the said heat radiating element and the said 40 return pipe, and devices embodied in both the supply pipe and the return pipe, the said devices acting upon the fluid flowing through the said supply pipe and through the said return pipe to create oppositely acting pressures through the said horizontal pipe connections to thereby effect equalization between the pressures in the supply pipe and the return pipe.

5. A heating system comprising two heat 50 radiating elements, a supply pipe leading from a source of heated fluid and located intermediate said heat radiating elements, two return pipes for returning the fluid to the said source, pipe connections leading 55 from the supply pipe to said heat radiating elements, a pipe leading from one of the said heat radiating elements to one of said return pipes, a pipe leading from the other of said heat radiating elements to the other 60 of said return pipes, means within the supply pipe for directing portions of the fluid which may be flowing therethrough into the said pipe connections through which they are supplied to the said heat radiating elements 65 and for permitting the remaining portion of

the fluid in the said supply pipe to flow forward therein, and means within each of the said return pipes which operates to retard the flow of fluid through each of the said return pipes.

6. A heating system comprising a heat radiating element, a supply pipe for supplying a heated fluid to said heat radiating element, a return pipe through which the heated fluid flows, a pipe connection between the said supply pipe and the said heat radiating element through which heated fluid flows to the said radiating element, a pipe connection between the said heat radiating element and the said return pipe through which heated fluid flows from said heat radiating element to said return pipe, a device located in the said supply pipe for directing heated fluid from said supply pipe through said first named pipe connection to the said heat radiating element, and a device located in said return pipe for retarding the flow of heated fluid through said second named pipe connection to thereby maintain the desired relationship between the pressures in the supply pipe and the return pipe.

7. A heating system comprising a heat radiating element, a supply pipe, a return pipe, a connection between the said pipes through which fluid flows from the supply pipe to the return pipe, the said connection including the said heat radiating element, a device embodied in each of said pipes each of which devices includes means whereby a portion of the fluid flowing through the pipe containing the same is deflected into the said connection, substantially as described.

8. A heating system comprising a heat radiating element, a supply pipe through which a heated fluid medium flows, a return pipe through which the heated fluid medium flows from the said heat radiating element, a pipe connection between the said supply pipe and the said return pipe, the said connection including the said heat radiating element, and devices embodied in the said supply and return pipes, the device embodied in the said supply pipe including means which deflects a portion of the heated fluid medium flowing through the said supply pipe into the said pipe connection, and the device embodied in the said return pipe including means which retards the flow of fluid from the said pipe connection into the said return pipe.

In testimony that I claim the foregoing as my invention, I have hereunto signed my name this 26th day of November A. D., 1927.

ALFRED J. RUDOLPH.
